UNITED STATES PATENT OFFICE.

CHARLES J. AHRENFELDT, OF NEW YORK, N. Y.

DESIGN FOR A PLATE OR SIMILAR ARTICLE.

SPECIFICATION forming part of Design No. 31,620, dated October 10, 1899.

Application filed July 20, 1899. Serial No. 724,566. Term of patent 7 years.

To all whom it may concern:

Be it known that I, CHARLES J. AHRENFELDT, a citizen of the United States, residing at the city of New York, county of New York, and State of New York, have invented and produced a new and original Design for a Plate or Similar Article, of which the following is a specification, reference being had to the accompanying drawings, forming a part hereof, like letters referring to like parts in each figure of the same.

In the said drawings, Figure 1 is a plan view of a plate with my design placed thereon. Fig. 2 is a medial vertical section of the same.

The ornamentation upon the plate is as follows:

A consists of two parts A', each resembling a horn-of-plenty crossed near their smaller and inner ends.

B consists of a central panel B' with ornamental border and a griffin's head in the center. From the lower part of the panel, on either side, proceed a series of leafed ornaments B², extending on curved lines and ter-

minating in volutes b. From these ornaments project at intervals stems B³, bearing flowers.

The two ornaments A and B are alternated to form a circular border or wreath, while in the center of the circle is an ornament C, consisting of a central panel C', having an ornamental border and scrolls in the center and surrounded by a wreath consisting of two-leaved stems C², united at the bottom, extending upwardly around the sides of the panel, and terminating above the same in flowers C³.

This design may be applied to articles other than plates.

What I claim is—

The design for a plate or similar article substantially as herein shown and described.

Signed at the city of New York this 14th day of July, 1899.

CHARLES J. AHRENFELDT.

Witnesses:

E. J. CONRAD,
E. T. GREINER.
